LOCK CONSTRUCTION

Henry F. Keil, Scarsdale, N. Y., assignor to Francis Keil & Son, Inc., a corporation of New York

Application June 26, 1934, Serial No. 732,451

33 Claims. (Cl. 70—47)

This invention relates to lock construction and more particularly to a key-controlled mechanism of the so-called "cylinder" type.

One of the objects of this invention is to provide a simple, inexpensive, and reliable lock construction of the above-mentioned character and more particularly one that may be quickly and easily assembled, in the course of manufacture or which may be with facility and convenience 10 disassembled for purposes of replacement, repair, or change of the parts or their relation and then reassembled. Another object is to provide a construction of the above-mentioned character that will be compact, inexpensive to manufacture, 15 simple to operate, and that will be also foolproof. Another object is to provide a lock construction which is armored against drilling, or the like, in a simple, inexpensive and compact manner, and, moreover, without creating unsightliness of 20 appearance. Another object is to provide a simple, inexpensive and practical connection between the key plug and operating bar and also to provide such a connection that is well adapted to meet varying conditions of practical use. 25 Other objects will be in part obvious or in part pointed out hereinafter.

The invention accordingly consists in the features of construction, combinations of elements, and arrangements of parts as will be exemplified 30 in the structure to be hereinafter described and the scope of the application of which will be indicated in the following claims.

In the accompanying drawings in which are shown several of the various possible embodiments of my invention,

Figure 1 is a vertical central sectional view through the lock mechanism as it appears when installed in a door, or the like;

Figure 2 is a transverse sectional view, as seen 40 along the line 2—2 of Figure 1;

Figure 3 is a plan view, as seen from the top in Figure 1, of the casing per se as the latter appears disassembled from the other parts shown in Figure 1;

Figure 4 is an end view, as seen from the left-hand end of Figure 1, more particularly as seen along the line 4—4 of Figure 1;

Figure 5 is a plan view of the connecting bar;

Figure 6 is a sectional view, as seen along the 50 line 6—6 of Figure 5, showing more clearly certain details of construction of the connecting bar;

Figure 7 is a detached side elevation showing the inner relation of the connecting bar with the key plug;

Figure 8 is a fragmentary central vertical sectional view, as seen substantially along the line 8—8 of Figure 4;

Figure 9 is a top plan view of a modified form 60 of mechanism;

Figure 10 is a front elevation thereof, as seen from the bottom in Figure 9;

Figure 11 is an end view, as seen from the left in Figure 9;

Figure 12 is a detached side elevation showing 5 the interconnection between the connecting bar and the key plug;

Figure 13 is a plan view of the connecting bar;

Figure 14 is a sectional view of the connecting bar, as seen along the line 14—14 of Figure 13, and 10

Figure 15 is a plan view of a member coacting to maintain the connection between connecting bar and related parts.

Similar reference characters refer to similar parts throughout the several views in the drawings.

Referring now to the drawings and more particularly to Figure 1, I have there shown my lock construction as it might be applied to a door, or the like, for actuating, under the control of a suitable key, a bolt or latch mechanism 10 suitably mounted upon the door 11, as upon the inside or left-hand face thereof, the key-controlled or lock mechanism being mounted in a hole 12 in the door 11, in a manner more clearly described hereinafter.

The lock mechanism includes a casing generally indicated at 13 suitably shaped, as by casting, or the like, to provide a front or escutcheon plate 14, preferably circular (see Figure 2) from the rear or left-hand side of which, as seen in Figures 1 and 3, extends a cylinder-like housing portion 15 along the top of which extends a tumbler housing portion 16 (see also Figure 4). The casing 13 is bored out through the cylinder portion 35 15 thereof, as at 17, in order rotatably to receive and mount the cylindrical key plug 18 whose forward or right-hand end (see Figure 1) is of larger diameter formed as by the spaced peripheral shoulders 19—20, the latter having therebetween an annular groove 21, the casing 13 being counterbored as at 22 to a larger diameter than the diameter of the bore 17 in order thus to accommodate the larger diameter portion 19—20 of the key plug 18; this counterbore 22 45 is preferably accommodated within the thickness of the front plate 14, the latter being made of suitable thickness for that purpose.

With the key plug 18 inserted into the bore and thus positioned as seen in Figure 1, the annular 50 or ring-shaped shoulder 19 of the key plug 18 fits into the angle of the counterbore 22 and thus limits movement of the key plug 18 in a direction toward the left, as viewed in Figure 1, and in that position of the parts, the left or rear end of the key plug 18 is preferably flush with the left-hand end of the cylindrical housing portion 15, as better appears in Figure 1.

The key plug 18 is provided with a suitably shaped key slot 23 extending lengthwise thereof 60

and preferably throughout the lower half portion thereof (see also Figure 2) and a suitably cross-sectioned key may thus be inserted into the key slot 23, the key being suitably serrated, notched or edged to coact with and control suitable tumbler devices which coact with the casing 13 to prevent or to permit rotation of the key plug 18 relative to the casing 13. In so far as certain features of my invention are concerned, these tumbler devices may take any suitable or appropriate form and number and illustratively and preferably they are in the form of so-called pin tumblers, as shown in Figure 1 and illustratively there are five sets.

Accordingly, the key plug 18 is provided with tumbler-receiving recesses 31, 32, 33, 34 and 35, these being generally cylindrical and extending from the upper face of the key plug 18 (with the latter in the position shown in Figures 1 and 2) down into communication with the key slot 23 in order thereby to expose to the latter and to a key inserted therein the pin tumblers 41, 42, 43, 44 and 45 respectively received in the aforesaid recesses.

These tumbler pins are of suitably differing lengths, as is understood in the art, so that, when the proper key is inserted into the key slot 23, these tumbler pins are lifted (as viewed in Figure 1) to bring their upper faces or edges substantially exactly to the periphery of the key plug 18 itself, thereby ejecting from the tumbler-receiving recesses in the key plug 18 the coacting pin tumblers 51, 52, 53, 54 and 55 which theretofore had projected from the tumbler-receiving housing portion 16 of the casing 13 into the key plug recesses, thereby precluding rotation of the key plug.

These tumbler pins 51, 52, 53, etc. are slidably mounted in tumbler-receiving recesses 61, 62, 63, 64 and 65, respectively, the latter being formed as by casting or drilling, in the housing portion 16, opening at their lower ends into the bore 17. These tumblers are spring-pressed downwardly by springs 71, 72, 73, 74 and 75, respectively, the springs being interposed between the tumblers and the upper closing wall of the tumbler-receiving recesses; this closing wall may be in the form of a plate 24 extending along the top of the housing portion 16 between flanges 16^a and 16^b (Figure 4) of the latter, these flanges being burried or pressed over to hold the plate 24 in place.

The tumbler-receiving recesses 31, 32, etc. in the key plug 18 and the tumbler-receiving recesses 61, 62, etc. in the casing 13 are respectively aligned when the key plug 18 has its ring-like shoulder or flange 19 bottoming in the counterbore 22 (Figure 1) and this alignment is maintained by a plate member 25 (Figures 1 and 2) that is received within the flange 14 and that coacts with the annular groove 21 of the key plug 18.

Not only is such alignment of the respective tumbler-receiving recesses and tumblers in the casing and key plug achieved and maintained but also, as later pointed out hereinafter, the resultant fixing of the axial position of the key plug 18 relative to the casing 13 and more particularly relative to the bored-out cylinder portion 15 thereof is made to coact in controlling and maintaining the interconnection, at the rear or left-hand end of the key plug 18 of the connecting or operating bar 28 which extends into the bolt mechanism 19; this unique coaction may be achieved by illustrative constructions and arrangements as are hereinafter described in great-

er detail and according to which the interconnection between key plug and connecting bar may not only be reliably maintained but may also be shiftable or capable of quick and easy rearrangement to meet certain of the varying conditions of practical use pointed out hereinafter. The above-mentioned plate member 25 may, furthermore, and in accordance with such coacting features of my invention, be made to maintain assembly of key plug with respect to the casing 10 while the above-mentioned interconnection is changed or shifted even though the member 25 otherwise aids in maintaining disconnection of the connecting bar from the key plug, thus preventing spilling of, disassembly of, or interference with, the relatively minute and otherwise numerous parts, such as the tumbler pins, springs, and the like, while on the other hand, the member 25 assures proper coaction between the cylindrical housing portion 15 of the casing, the connecting bar itself, and the rear end of the key plug.

More specifically, there is formed in the front plate 14 a slot or guideway 26 (Figures 2 and 3) whose width, as viewed in Figure 2, preferably is somewhat greater than the diameter of the front or flanged (19-20) end of the key plug 18 and whose depth or vertical dimension is preferably such that it extends from the peripheral face of the front plate 14 downwardly preferably to 30 about the axis of the counterbore 22, thereby intersecting the counterbore. Into this slot 26, which may be cast or otherwise formed, is snugly and slidably fitted the above-mentioned plate member 25, the latter being made preferably of hardened steel or other suitable hard metal capable adequately to resist the action of a tool such as a drill, or the like. The plate 25, shaped as is better shown in Figure 2, has its lower edge 25^a cut or shaped on a curve whose radius is the same as the radius of curvature of the bottom of the annular groove 22 (Figure 1) between the shoulders 19-20 of the key plug 18, annular groove 22, plate 25, and plate-receiving slot 26, being of substantially the same thickness or dimension (as seen in Figure 1) so that the lower edge portions of the plate 25 ride into the annular groove 21 with sufficient snugness to prevent movement in an axial direction of the key plug 18 while permitting freedom of rotation of the latter, and the plate 25 being received within the slot 26 with sufficient snugness to prevent play of the plate 25 relative to the casing 13. Thus, the key plug 18 is dependably held in assembled relation to the casing 13 and the above-mentioned alignment of the respective tumbler recesses and tumblers dependably maintained.

The vertical or side edges of the slot 26, as seen in Figure 2, are preferably parallel and equidistantly spaced from a vertical line drawn through the axis of the key plug 18 in which case the plate 25 will be seen to be symmetrical. Though plate 25 is received within the slot 26 with sufficient snugness or tightness of fit, so as to be securely held therein by frictional contact with the walls 65 of the slot, nevertheless, I prefer to lock the plate 25 in position and for that purpose I may employ a screw 27 (Figures 1, 4 and 3) threaded into and through that portion of the front plate 14 that is to the rear of the slot 26 so that, by tightening up the screw 27 it clamps the plate 25 between itself and the front wall portion of the slot 26 itself. In that position and because of the hardness of the material of the plate 25, the latter gives a protection to the lock mechanism 75

that is of great practical importance. The expansion of the plate 25 both vertically and horizontally (see Figure 2) is such as to form a substantial barrier against access, as by drilling 5 through the front plate 14, to the tumbler-receiving housing portion 16, and thus it becomes impossible to drill into the housing 16 in order thereby to drill away or dislodge the tumblers 51, 52, etc., and thereby endeavor to achieve rotation 10 of the key plug 18.

With the fixing of the rotatable key plug 18 in position within the casing 13, as above described, there has simultaneously been brought about also a fixing of the interconnection of the connecting bar 28, which extends to the left into operative engagement with the bolt mechanism 10 (Figure 1), to the left or rear end of the key plug 18. The connecting bar 28, conveniently in the form of a stamping of heavy sheet metal, is substantially T-shaped, as is better shown in Figure 5, having at its end transversely projecting lugs 28^a and 28^b, the latter, however, being bent in opposite directions out of the plane of the bar 28 itself, as is better shown in Figure 6, giving the bar 28, therefore, an effective T-shape, either as viewed in Figure 5 or as seen from the top in Figure 5, the left or rear end of the key plug 18 is provided with a T-slot 18^a (see Figures 8 and 7) open-ended at both ends, and into the T-slot 18^a 20 the connecting bar 28 is slid, the throat of the T-slot being of a width substantially equal to the thickness of the connecting bar 28, the oppositely curved ears or lugs 28^a—28^b of the connecting bar being thereby made to extend into the wider or base portion of the T-slot 18^a, the connecting bar 28 being thus non-rotatably connected to the key plug 18 and also held against separation therefrom by movement in the direction of the axis of the key plug 18 itself. But 30 the opposite open ends of the T-slot 18^a, terminating as above mentioned in the peripheral or cylindrical face of the key plug, are now closed (see Figure 8) by the cylindrical portion 15 of the casing 13, so that movement of the connecting bar 28 along the T-slot 18^a, thus to disengage the bar from the key plug, is prevented.

It frequently happens, however, in practice, because of variations in type or construction of the bolt or latch mechanism 10 (Figure 1), that the relation of the operating or connecting bar 28 to the key plug 18 has to be changed. For example, assuming that the key plug 18 and the casing 13 have the normal or locked positions shown in Figure 1, the bolt mechanism 10 may 50 be of a type or kind or may be so positioned that the plate of the connecting bar 28 has to be vertical while, on the other hand, due to such factors as above-mentioned, the mechanism 10 may be of a type that requires the plane of the connecting bar 28 to be horizontal and hence displaced 90° from what might be the requirement under other conditions or with another type of bolt mechanism 10. Or, stated differently, the slot in the roll-back or like device in the mechanism 10, depending upon the position of the latter, the type or construction of the latter, and other factors, and which slot is to receive the connecting bar 28, extends either vertically or horizontally, and the key-controlled mechanism 60 must be made to meet these possible conditions without necessitating the impracticable rotating of the entire casing 13 through 90°.

Accordingly, I provide for meeting this peculiar condition and hence, referring now to Figure 4, 70 I provide another T-slot 18^b in the rear end of

the key plug 18, T-slot 18^b, however, extending at right angles and thus intersecting the above-mentioned T-slot 18^a, as is clearly shown in Figure 4. Into either of these T-slots, therefore, the operating bar 28 may be inserted, and in order to give access to the open ends of the T-slots 18^a and 18^b, without requiring disassembly of the key plug 18 from the casing 13 and related parts, I provide in the upper rear portion of the housing portion 15 (see now Figures 3 and 10 15) and immediately to the rear or left of the tumbler housing portion 16, a slot 15^a whose peripheral extent or dimension is preferably at least equal to the largest cross-sectional dimension of the T-slot 18^a or 18^b.

Extending about this left or rear end of the cylindrical housing portion 15 and thus intersecting the slot 15^a is an external peripherally extending groove 15^b (Figures 3 and 4) and in this external peripheral groove 15^b is seated a 20 split ring 29 made of a spring wire tending to contact and hence acting always to grip the cylindrical housing portion 15. As is better shown in Figure 4, adjacent one end of the split ring 29, the latter is provided with an inwardly directed U-shaped bend 29^a suitably dimensioned to snugly fit into the slot 15^a (see Figures 3 and 4) and substantially fill the gap caused by said slot 15^a, at least in so far as the slot 15^a permits movement in a radial direction of the 30 connecting bar 28 along a T-slot 18^a or 18^b. Accordingly, the portion 29^a of the split spring ring 29 substantially closes the slot 15^a and thus, with the remaining portions of the cylindrical housing portion 15 coacting always to maintain 35 the T-slots closed, no matter what rotary position the key plug 18 may be given.

If, now, it is desired to remove the operating bar 28 from the T-slot 18^a (see Figure 4), the portion 29^a of the split ring 29 is forced out of 40 the slot 15^a, against the spring action of the split ring 29 itself, and the latter is given a slight counterclockwise rotation, as viewed in Figure 4, thus bringing the portion 29^a into the peripheral groove 15^b but to the left of the slot 15^a, the 45 latter being thereby exposed through the gap between the ends of the split ring 29.

The key plug 18 is thereupon rotated, with the aid to a key, of course, where necessary, to bring one end of the T-slot 18^a in line with the slot 15^a, 50 whereupon the connecting bar 28 may be slid upwardly, as viewed in Figure 4, out of the T-slot 18^a and through the slot 15^a, and thus disengaged from the key-controlled mechanism. Thereupon, the key plug 18 is given a 90° rotation, thus to 55 bring the T-slot 18^b with one end thereof juxtaposed to the open slot 15^a, whence the connecting bar 28 is now inserted through the slot 15^a and into the T-slot 18^b, the shank of the connecting bar 28 being snugly received between the 60 narrower portions of the T-slot 18^b and the laterally projecting lugs 28^a and 28^b projecting into the wider portions of the T-slot 18^b, assuming a relation such as is shown in Figure 7, the mechanical interrelation being the same as theretofore 65 existed between the connecting bar 28 and the T-slot 18^a.

The split ring 29 is thereupon moved about the external groove 15^b in clockwise direction, as 70 viewed in Figure 4, whereupon the inwardly directed portion 29^a thereof snaps into the slot 15^a, thus closing the latter and thus again coacting with the cylindrical housing portion and as a part of the latter to prevent displacement in 75

a radial direction of the connecting bar 28 relative to the key plug.

In the course of these operations, it will be perceived that the connecting bar 28 has been shifted through an angle of 90° relative to the key plug 18 and has thus been adapted to meet the changed requirements or conditions met with in practice and illustratively set forth above. This change in interrelation between the operating bar and the key plug will be seen to be possible of achievement without having to remove the key plug from the casing 13.

However, there may be and generally are conditions in practice under which it is necessary or desirable to remove the key plug 18 from the casing 13; for example, for purposes of repair, replacement, or change of parts, particularly of the tumblers, or even for purposes of fitting a new key. In such case, the casing 13 having been

removed from the door 11, the set screw 27 (Figures 1, 3 and 4) is loosened up and the combined armor and locking plate 25 sufficiently withdrawn relative to its slot 26 to disengage it from the annular groove 21 (Figure 1) in the key plug 18. To facilitate such withdrawal, I cut away, as at 14^a (Figures 3 and 1) the rear wall of the slot 26, preferably in line with the tumbler-receiving housing portion 16, thus to expose an upper portion of the rear face of the plate 25. At such exposed portion of the plate 25 I provide in the latter a hole 25^b (Figures 1 and 2) into which a suitable implement may be inserted to raise the plate 25 against the friction of its engagement with the slot 26.

It will be noted, however, that, where it is necessary to attach or detach the connecting bar 28, or to shift or change its relation to the key plug or to the bolt mechanism 10, such operation or operations may be quickly and speedily performed without having to disturb the relation of the key plug, casing, tumbler, tumbler recesses, springs, and like parts, the plate member 25 dependably holding the latter against disarrangement or disassembly. Entire freedom of action or manipulation with respect to the connection of the connecting bar to the key plug is thus permitted.

A preferred construction, however, for achieving such results as are above pointed out and for achieving coaction with the armor plate member 25, some of which coactions are above indicated, I have shown in Figures 9-15 inclusive, in which, referring now to Figures 9, 10 and 11, the casing and key plug construction and tumbler arrangement, including the feature of the plate member 25, are substantially the same as described in detail above in connection with Figures 1, 2, 3, 4 and 8, and these parts, in Figures 9, 10 and 11, need not, therefore, be described in detail, excepting for certain features pointed out later herein. It will therefore be noted that the casing 13 (Figures 9, 10 and 11) again has the front disk-like plate 14 slotted as above described to receive the armor plate member 25, the latter being capable of being locked in position by the screw 27, and coacting with the annular groove formed between the annular or ring-like shoulders 19-20 in the front end of the key plug 18. The casing 13 again has the lower cylindrical housing portion 15 which is bored out rotatably to receive the key plug 18 and extending upwardly therefrom is the tumbler-receiving housing portion 16, containing the tumblers for coaction with the key plug tumblers and key, as above described. The rearward (toward the left) extension of the cylindrical hous-

ing portion 15 is again present but the lugs or ears by which the casing and related parts are secured in the hole in the door and corresponding to the lugs or ears 38 and 39 of Figure 3 are preferably formed on this rearward extension of the cylindrical housing portion 15, being indicated in Figures 9 and 11 at 138 and 139 respectively.

Or, viewed in a different light, and as is better shown in Figure 11, this rearward extension of 10 the housing portion 15 is upwardly extended as at 15^g and for greater compactness and convenience the lugs or ears 138 and 139 extend respectively to the left and right of this upward extension 15^g, as seen in Figure 11. 15

With the added metal thus provided by the portion 15^g, I am enabled to provide therein a slot 15^h (Figures 9 and 10) extending transversely of the bore 17 in which the key plug 18 is rotatably mounted, slot 15^h having a width, 20 as viewed in Figure 11, substantially equal to the diameter of the bore 17, all for a purpose about to be described.

The left or rear end of the key plug 18 is provided with two slots 18^g and 18^h (Figures 11 and 25 12), extending at right angles to each other and as will be later more apparent, these slots need not be undercut and thus lend themselves to less expensive manufacture, simplifying the casting, or milling operations. One of the slots, such as 20 slot 18^h extends in the plane of the key slot 23 in the key plug 18, just as the slot 18^a of the key plug of Figure 8 extends in the plane of the key slot 23, all as above described.

The connecting bar preferably takes the form 35 better shown in Figures 13 and 14, the connecting bar 128 there shown being substantially T-shaped, having end lugs 128^a and 128^b which, as is better shown in Figure 14, can be and preferably are in the plane of the connecting bar 128 40 itself; that need not be bent out of that plane as was the case with the illustrative form shown in Figures 5 and 6 and above described.

The right-hand end of the connecting bar 128, as viewed in Figure 13, is receivable in either of 45 the slots 18^g or 18^h in the rear end of the key plug 18, for reasons above already described in some detail, and in Figures 10 and 11 that end of connecting bar 128 is shown received within slot 18^h. 50

With the plate member 25 fixing the position of key plug 18, as above described, the plane of the bottoms of the end slots 18^g and 18^h in the key plug 18 (see now Figure 10) is in line with the right-hand wall of a slot 15^j (see also Figure 55 9) that is cut in the casing or extension portion 15^g from the upper edge thereof right down into the bore 17, slot 15^j connecting at its left-hand end (see Figures 9 and 10) with the transverse slot 15^h. Where slot 15^j extends to the right or 60 forwardly of the transverse slot 15^h, I provide a slot 15^k in the extension portion 15^g to the left or rearwardly of transverse slot 15^h (see Figures 9, 10 and 11), slot 15^k extending from the top edge of the extension portion 15^g right down into 65 the bore 17 and also connecting with the transverse slot 15^h (Figure 9). Accordingly, with either slot 18^g or 18^h extending vertically, a position achieved by rotating the key plug 18, as viewed in Figure 11, that slot of the two which 70 is thus made to extend vertically, illustratively slot 18^h (Figures 10 and 11) is thus brought into alignment with the vertical slots 15^k and 15^j above described, these two slots being intersected by the transverse slot 15^h, and accordingly con- 75

necting bar 128 may be slid in the direction of its own plane (vertically, as viewed in Figure 10) through the slots 15^k and 15^j and thus into the plug slot 18^h, much in the same manner as the connecting bar 28 of Figures 2-8 may be related to a transverse slot in the key plug when the cylindrical casing portion is opened up as at the slot 15^a (Figure 3) therein upon moving the ring member 29 out of slot-closing position.

The composite slot 15^k-15^j of Figures 9, 10 and 11, thus transversely opening up the cylindrical housing portion 15, I also provide to be closed or opened at will; for this purpose I employ a plate-like member 129 (see now Figure 15) shaped to be snugly fitted and received into the transverse slot 15^h (Figures 9 and 11); the plate member 129 accordingly has parallel side edges adapted to mate with the parallel and vertically extending sides, as viewed in Figure 11, of the transverse slot 15^h, joined by a lower arcuate edge 129^a shaped or curved so as to snugly bottom in, or mate with the curvature of, the bore 17 (see Figure 11), and when thus bottoming in the bore 17, the upper horizontal edge 25 of the plate member 129 preferably mates with the upper horizontal edge of the extension portion 15^g (Figure 11) of the housing. Now plate member 129 is virtually in the form of a ring, having an opening therein 129^b of a diameter 30 slightly in excess of the width of the connecting bar 128 (Figure 13) so that the latter may pass therethrough and be freely rotated relative thereto, but lugs 128^a-128^b (Figure 13) preventing the complete passage through the ring member 129 of the connecting bar 128.

Accordingly, when sliding the connecting bar 128 downwardly (Figure 10) through the composite slot 15^k-15^j, and the ring or plate member 129 having first been slipped onto the connecting bar 128, the member 129 moves downwardly into its slot 15^h as the connecting bar 128 passes downwardly through the slots 15^k-15^g, emerges from the latter, and seats the head end, with lugs 128^a-128^b, into plug slot 18^h, resulting in a relation of the parts as is better shown in Figures 9, 10 and 11.

Withdrawal of the operating bar 128 in a direction toward the left, as seen in Figure 10, is precluded by the plate member 129, whose aperture 129^b does not permit the passage therethrough of the lugs 128^a-128^b. With the plate member 25 preventing the key plug 18 from moving toward the right, as viewed in Figures 9 and 10, and with the member 129 preventing movement of the connecting bar 128 toward the left, as viewed in these figures, the telescopic connection between key plug 18 and connecting bar 128, the latter fitting into the slot 18^h (or 18^g, as the case may be), is dependably and effectively maintained, and hence the rotation of the connecting bar 128 with consequent actuation of the bolt mechanism 10 (Figure 1) in response to rotation of the key plug 18 under the control of a key must follow.

Referring again to Figure 15, the lower portion of member 129 is provided with a lug or tab 129^c which, referring now to Figures 10 and 11, is received within a slot 15^m in the lower end of the cylindrical casing portion 15, slot 15^m being, of course, in alignment with the transverse slot 15^h and thus dependably anchoring the lower end of the member 129.

Preferably the member 129 is relatively snugly or tightly fitted into its slot 15^h, or 15^m, or both, 75 so that it will be held within the slot by the fric-

tional gripping action of the walls of the latter; it may be, for example, in the nature of a tap-fit as distinguished from a force-fit. And to facilitate withdrawal of the member 129 from its slot without having to subject the connecting bar 128 to any strain or stress, I provide in the member 129 an aperture 129^e positioned so that, when the member 129 is within its slots 15^h-15^m, aperture 129^e is in alignment with the vertical slot 15^k (see Figure 11), the aperture being thus accessible from the rear of the casing 13. Accordingly, any suitable instrument may be inserted through the slot 15^k into the aperture 129^e and member 129, and the latter withdrawn by such instrument against whatever forces hold the member in its slot.

Should such withdrawal of the holding member 129 be effected, plate member 25 (Figures 9 and 10) holds the key plug 18 against removal from the casing 13, and thus precludes spilling of the tumblers, springs, or like small parts. Replacement of the connecting bar which, it is to be noted, is disconnected from the key plug and casing at the same time that the member 129 is withdrawn as above described, is a simple operation, 25 requiring only a reverse of what has just been described, and if it is necessary that the relation between connecting bar 128 and the key plug 18 be shifted 90°, the replacement of the connecting bar 128 is made after key plug 18 has been given a 90° 30 turn, as with the key, to bring the other slot, illustratively slot 18^g (Figure 11) in alignment with the composite vertical slot 15^k-15^j (Figure 10).

Once the connecting bar 128 is thus inserted into an end slot in the key plug and the member 129 returned to its slots 15^h-15^m so as again to form a part of or to restore the cylindrical housing portion 15, the latter, now having its composite transverse slot 15^k-15^j closed, effectively prevents the connecting bar 128 from riding, in a 40 transverse direction, out of whichever of the various slots in the plug 18 that it is seated in.

Moreover, just as was the case with the construction above described in connection with Figures 1-8 inclusive, any side or transverse thrusts 45 on or by the connecting bar, that is, in a radial direction relative to the key plug, are dependably and reliably resisted by the wall of the bore in which the key plug is rotatably mounted, and thus disconnection of the connecting bar from any 50 plug by movement of the former along a radius (or slot) of the latter is reliably resisted by the wall of the bore to which such side or transverse thrusts are transmitted.

As above indicated, the construction just described and shown in Figures 9-14 inclusive, is in all respects other than those just mentioned, the same as that set forth in connection with Figures 1-8 inclusive.

The upper edge 25^c (Figure 2 or 11) of the 60 plate 25 has a curvature that matches the curved periphery of the front plate 14 so that when the plate 35 is in operative or downward position, the plate 25 does not project from the periphery of the front plate 14. Moreover, the construction, 65 when installed, as illustrated in Figure 1, is such that the upper end of the slot 26, and hence also the upper edge 25^c of the plate 25, are concealed and inaccessible inasmuch as the front plate 14 is snugly received within a suitably stepped or 70 flanged ring 30 (Figure 1) which covers over the periphery of the front plate 14, and, moreover, has portions that extend to the rear of the latter, such portions of ring 30 resting against the right-hand face of the door 11, as shown in Figure 1, 75

and not being removable from the front or right-hand side of the door 11.

This because of the interfitting relation between the ring 30 and the front plate 14 and also the manner of securing the casing 13 in the hole 12 in the door 11. In effect, the door 11 and the ring 30 are securely clamped between a back plate 36 (Figure 1) that rests against the inner or left-hand face of the door 11, extending underneath the casing of the lock mechanism 10, and the front plate 14 of the casing 13; this clamping is achieved by means of screws 37 that pass through the back plate 36, excepting for their heads, and they are threaded into threaded openings in the ears 38 and 39 (Figure 3 and 4) integrally formed with the left or rear portion of the casing 13. A suitable hole in the back plate 36 permits the passage therethrough of the connecting bar 28 as it extends toward the left (Figure 1) into the slot of the roll-back or other device by which the bolt mechanism 10 is actuated.

Thus, it will be seen that there has been provided in this invention a lock construction in which the various objects hereinbefore set forth, together with many thoroughly practical advantages, are successfully achieved. It will be seen that the construction is of a thoroughly practical nature, is inexpensive, is time- and labor-saving in assembly or disassembly, and is of thoroughly dependable action in use. Moreover, also, dependable protection against drilling into vital parts of the key-controlled mechanism is afforded in a thoroughly reliable and simple manner and thus greater security achieved. Moreover, the construction is compact and neat and particularly as to the casing and key plug lends itself readily to casting, particularly die casting.

As many possible embodiments may be made of the above invention and as many changes might be made in the embodiment above set forth, it is to be understood that all matter hereinbefore set forth or shown in the accompanying drawings is to be interpreted as illustrative and not in a limiting sense.

I claim:—

1. In lock construction, in combination, a casing having an open-ended cylinder portion containing a bore, a key plug having a key slot and rotatably fitted into said bore, tumbler means controllable by a key inserted into said key slot for coaction with said key plug and casing, an operating bar, means forming a detachable interconnection between said operating bar and the rear end of said key plug and capable of disconnection only upon moving said connecting bar in the direction of a radius of said key plug, and means releasably holding said key plug against movement in an axial direction to maintain the key plug and tumbler means and casing in proper alignment and to cause a wall of said bore to prevent movement in a radial direction of said operating bar and thus maintain interconnection thereof with said key plug.

2. In lock construction, in combination, a casing having an open-ended cylinder portion containing a bore, a key plug having a key slot and rotatably fitted into said bore, tumbler means controllable by a key inserted into said key slot for coaction with said key plug and casing, an operating bar, means forming a detachable interconnection between said operating bar and the rear end of said key plug and capable of disconnection upon moving said connecting bar in the direction of a radius of said key plug, said key plug having a groove extending in the direction of its periph-

ery and said plug normally having such a position that a wall of said bore blocks movement of said operating bar along a radius, and means projecting from said casing into said groove to prevent axial displacement of said key plug and thereby to hold said connecting bar and said plug against disconnection.

3. In lock construction, in combination, a casing having an open-ended cylinder portion containing a bore, a key plug having a key slot and rotatably fitted into said bore, tumbler means controllable by a key inserted into said key slot for coaction with said key plug and casing, an operating bar, means forming a detachable interconnection between said operating bar and the rear end of said key plug and capable of disconnection upon moving said connecting bar in the direction of a radius of said key plug, said key plug having a peripheral groove adjacent its forward end and said casing having a slot in the front wall thereof, said slot extending in a direction transversely to the axis of the key plug and opening into said bore, and a plate-like member of relatively hard metal fitted into said last-mentioned slot and engaging into the peripheral groove in said key plug, thereby to hold the latter against axial displacement and in a position to cause a wall of said bore to prevent movement in a radial direction of said connecting bar relative to the plug.

4. In lock construction, in combination, a casing having an open-ended cylinder portion containing a bore, a key plug having a key slot and rotatably fitted into said bore, tumbler means controllable by a key inserted into said key slot for coaction with said key plug and casing, an operating bar, means forming a detachable interconnection between said operating bar and the rear end of said key plug and capable of disconnection upon moving said connecting bar in the direction of a radius of said key plug, said key plug having a peripheral groove adjacent its forward end and said casing having a slot in the front wall thereof, said slot extending in a direction transversely to the axis of the key plug and opening into said bore, and a plate-like member of relatively hard metal fitted into said last-mentioned slot and engaging into the peripheral groove in said key plug, thereby to hold the latter against axial displacement and in a position to cause a wall of said bore to prevent movement in a radial direction of said connecting bar relative to the plug, said last-mentioned slot and hence the plate received therein having a width equal to or greater than the width of that portion of said casing with which said tumbler means coacts, thereby to prevent a tool like a drill from passage therethrough and into said portion of said casing.

5. In lock construction, in combination, a casing having an open-ended cylinder portion containing a bore, a key plug having a key slot and rotatably fitted into said bore, tumbler means controllable by a key inserted into said key slot for coaction with said key plug and casing, an operating bar, means forming a detachable interconnection between said operating bar and the rear end of said key plug and capable of disconnection upon moving said connecting bar in the direction of a radius of said key plug, said key plug having a peripheral groove adjacent its forward end and said casing having a slot in the front wall thereof, said slot extending in a direction transversely to the axis of the key plug and opening into said bore, and a plate-like mem-

- ber of relatively hard metal fitted into said last-mentioned slot and engaging into the peripheral groove in said key plug, thereby to hold the latter against axial displacement and in a position to cause a wall of said bore to prevent movement in a radial direction of said connecting bar relative to the plug, and releasable means accessible from a face of said casing other than the front face thereof for locking said plate against withdrawing movement relative to its slot.
6. In lock construction, in combination, a casing having an open-ended cylinder portion containing a bore, a key plug having a key slot and rotatably fitted into said bore, tumbler means controllable by a key inserted into said key slot for coaction with said key plug and casing, an operating bar, means forming a detachable interconnection between said operating bar and the rear end of said key plug and capable of disconnection upon moving said connecting bar in the direction of a radius of said key plug, said key plug having a peripheral groove adjacent its forward end and said casing having a slot in the front wall thereof, said slot extending in a direction transversely to the axis of the key plug and opening into said bore, and a plate-like member of relatively hard metal fitted into said last-mentioned slot and engaging into the peripheral groove in said key plug, thereby to hold the latter against axial displacement and in a position to cause a wall of said bore to prevent movement in a radial direction of said connecting bar relative to the plug, and a screw threaded through a wall of said last-mentioned slot other than the front wall thereof for engagement with said plate and for locking the latter against withdrawing movement relative to its slot.
7. In lock construction, in combination, a casing having an open-ended cylinder portion containing a bore, a key plug having a key slot and rotatably fitted into said bore, tumbler means controllable by a key inserted into said key slot for coaction with said key plug and casing, an operating bar, means forming a detachable interconnection between said operating bar and the rear end of said key plug and capable of disconnection upon moving said connecting bar in the direction of a radius of said key plug, said key plug having a peripheral groove adjacent its forward end and said casing having a slot in the front wall thereof, said slot extending in a direction transversely to the axis of the key plug and opening into said bore, and a plate-like member of relatively hard metal fitted into said last-mentioned slot and engaging into the peripheral groove in said key plug, thereby to hold the latter against axial displacement and in a position to cause a wall of said bore to prevent movement in a radial direction of said connecting bar relative to the plug, and means for closing the open end of said second-mentioned slot.
8. In lock construction, in combination, a casing having an open-ended cylinder portion containing a bore, a key plug having a key slot and rotatably fitted into said bore, tumbler means controllable by a key inserted into said key slot for coaction with said key plug and casing, an operating bar, means forming a detachable interconnection between said operating bar and the rear end of said key plug and capable of disconnection upon moving said connecting bar in the direction of a radius of said key plug, said key plug having a peripheral groove adjacent its forward end and said casing having a slot in the front wall thereof, said slot extending in a direction transversely to the axis of the key plug and opening into said bore, and a plate-like member of relatively hard metal fitted into said last-mentioned slot and engaging into the peripheral groove in said key plug, thereby to hold the latter against axial displacement and in a position to cause a wall of said bore to prevent movement in a radial direction of said connecting bar relative to the plug, and means interlocked with said front wall when the mechanism is installed for closing the open end of said last-mentioned slot.
9. In lock construction, in combination, a casing having an open-ended cylinder portion containing a bore, a key plug having a key slot and rotatably fitted into said bore, tumbler means controllable by a key inserted into said key slot for coaction with said key plug and casing, an operating bar, means forming a detachable interconnection between said operating bar and the rear end of said key plug and capable of disconnection upon moving said connecting bar in the direction of a radius of said key plug, said key plug having a peripheral groove adjacent its forward end and said casing having a slot in the front wall thereof, said slot extending in a direction transversely to the axis of the key plug and opening into said bore, and means mounted in said second-mentioned slot and engaging into the peripheral groove in said key plug for holding the latter against axial displacement and in a position to cause a wall of said bore to block movement of said operating bar in a radial direction relative to said key plug.
10. In lock construction, in combination, a casing having an open-ended cylinder portion containing a bore, a key plug having a key slot and rotatably fitted into said bore, the rear end of said key plug having a transversely extending undercut slot open at a side of said key plug, a connecting bar having an end portion shaped to move into said slot upon movement of said bar in the direction of the radius of said plug, thereby to interlock with said plug, and means for holding said plug against axial displacement relative to said casing and in such a position relative to the latter that a wall of said bore closes off the open end of said undercut slot.
11. In lock construction, in combination, a casing having an open-ended cylinder portion containing a bore, a key plug having a key slot and rotatably fitted into said bore, the rear end of said key plug having a plurality of undercut slots therein extending at an angle to each other and each opening in the periphery of said plug, the wall of said bore having an axial extent sufficient to encompass the portions of the plug in which said slots open, the wall of said bore having a portion cut away thereby to expose, upon appropriate rotation of said plug, the open end of a slot, a connecting bar having an end portion shaped to pass through said cut away portion of said bore wall and to interlock with an undercut slot aligned with said cut away portion, thereby to become interlocked with said key plug, and releasable means for closing off said cut away portion of said bore wall.
12. In lock construction, in combination, a casing having an open-ended cylinder portion containing a bore, a key plug having a key slot and rotatably fitted into said bore, the rear end of said key plug having a plurality of undercut slots therein extending at an angle to each other and each opening in the periphery of said plug, the wall of said bore having an axial extent sufficient

- to encompass the portions of the plug in which said slots open, the wall of said bore having a portion cut away thereby to expose, upon appropriate rotation of said plug, the open end of a slot, a connecting bar having an end portion shaped to pass through said cut away portion of said bore wall and to interlock with an undercut slot alined with said cut away portion, thereby to become interlocked with said key plug, and spring-mounted means yieldably movable into or out of the cut away portion of the wall of said bore.

13. In lock construction, in combination, a casing having an open-ended cylinder portion containing a bore, a key plug having a key slot and rotatably fitted into said bore, the rear end of said key plug having a plurality of undercut slots therein extending at an angle to each other and each opening in the periphery of said plug, the wall of said bore having an axial extent sufficient to encompass the portions of the plug in which said slots open, the wall of said bore having a portion cut away thereby to expose, upon appropriate rotation of said plug, the open end of a slot, a connecting bar having an end portion shaped to pass through said cut away portion of said bore wall and to interlock with an undercut slot alined with said cut away portion, thereby to become interlocked with said key plug, the exterior of the wall of said bore having a peripheral groove intersecting the cut away portion thereof, and means having a gap therein and rotatably carried in said groove adapted upon rotary movement thereof to register said gap with said cut away portion or to move it out of registry therewith.

14. In lock construction, in combination, a casing having an open-ended cylinder portion containing a bore, a key plug having a key slot and rotatably fitted into said bore, the rear end of said key plug having a plurality of undercut slots therein extending at an angle to each other and each opening in the periphery of said plug, the wall of said bore having an axial extent sufficient to encompass the portions of the plug in which said slots open, the wall of said bore having a portion cut away, thereby to expose, upon appropriate rotation of said plug, the open end of a slot, a connecting bar having an end portion shaped to pass through said cut away portion of said bore wall and to interlock with an undercut slot alined with said cut away portion, thereby to become interlocked with said key plug, and a ring-like member rotatably engaged with the exterior of said bore wall having a portion that may be moved, upon rotation relative to said bore wall, into a position to close the cut away portion of the latter or into a position to expose said portion.

15. In lock construction, in combination, a casing having an open-ended cylinder portion containing a bore, a key plug having a key slot and rotatably fitted into said bore, the rear end of said key plug having a plurality of undercut slots therein extending at an angle to each other and each opening in the periphery of said plug, the wall of said bore having an axial extent sufficient to encompass the portions of the plug in which said slots open, the wall of said bore having a portion cut away, thereby to expose, upon appropriate rotation of said plug, the open end of a slot, a connecting bar having an end portion shaped to pass through said cut away portion of said bore wall and to interlock with an undercut slot alined with said cut away portion, thereby to become interlocked with said key plug, and a split spring ring gripping the exterior of the wall of said bore and movable relative to the latter to close or to expose the cut away portion therein.

16. In lock construction, in combination, a casing having an open-ended cylinder portion containing a bore, a key plug having a key slot and rotatably fitted into said bore, the rear end of said key plug having a plurality of undercut slots therein extending at an angle to each other and each opening in the periphery of said plug, the wall of said bore having an axial extent sufficient to encompass the portions of the plug in which said slots open, the wall of said bore having a portion cut away thereby to expose, upon appropriate rotation of said plug, the open end of a slot, a connecting bar having an end portion shaped to pass through said cut away portion of said bore wall and to interlock with an undercut slot alined with said cut away portion, thereby to become interlocked with said key plug, the exterior of the wall of said bore having a peripheral groove intersecting the cut away portion thereof, and a split spring ring rotatably mounted in said groove and having an inwardly directed portion normally seated in the cut away portion of said wall.

17. In lock construction, in combination, a casing having an open-ended cylinder portion containing a bore, a key plug having a key slot and rotatably fitted into said bore, the rear end of said key plug having a plurality of undercut slots therein extending at an angle to each other and each opening in the periphery of said plug, the wall of said bore having an axial extent sufficient to encompass the portions of the plug in which said slots open, the wall of said bore having a portion cut away thereby to expose, upon appropriate rotation of said plug, the open end of a slot, a connecting bar having an end portion shaped to pass through said cut away portion of said bore wall and to interlock with an undercut slot alined with said cut away portion, thereby to become interlocked with said key plug, the exterior of the wall of said bore having a peripheral groove intersecting the cut away portion thereof, and means having a gap therein and rotatably carried in said groove adapted upon rotary movement thereof to register said gap with said cut away portion or to move it out of registry therewith.

18. In lock construction, in combination, a casing having an open-ended cylinder portion containing a bore, a key plug having a key slot and rotatably fitted into said bore, the rear end of said key plug having a transversely extending slot open at a side of said key plug, a connecting bar having an end portion that may be moved into said transverse slot upon movement of said bar in the direction of a radius of said plug, and means for holding said plug against axial displacement relative to said casing and in such a position relative to the latter that a wall of said bore closes off the open end of said transverse slot.

19. In lock construction, in combination, a casing having an open-ended cylinder portion containing a bore, a key plug having a key slot and rotatably fitted into said bore, the rear end of said key plug having a transversely extending slot open at a side of said key plug, said cylinder portion having a slot in the wall of the bore thereof with which the open end of said transverse slot may be made to register upon appropriate rotation of the key plug, a connecting bar having an end portion shaped to pass through said third-mentioned slot and into said transverse slot upon said two slots being brought into registry, thereby non-rotatably to interconnect said connecting bar and said key plug, and means mounted and carried by said casing for holding said connecting bar against movement out of the open end of said transverse slot if the latter subsequently is brought into registry with said third-mentioned slot.

20. In lock construction, in combination, a casing having an open-ended cylinder portion containing a bore, a key plug having a key slot and rotatably fitted into said bore, the rear end of said key plug having a transversely extending slot open at a side of said key plug, said cylinder portion having a slot in the wall of the bore thereof with which the open end of said transverse slot may be made to register upon appropriate rotation of the key plug, a connecting bar having an end portion shaped to pass through said third-mentioned slot and into said transverse slot upon said two slots being brought into registry, thereby non-rotatably to interconnect said connecting bar and said key plug, and means carried by said casing for holding said connecting bar and said key plug against relative movement in an axial direction.

20. In lock construction, in combination, a casing having an open-ended cylinder portion containing a bore, a key plug having a key slot and rotatably fitted into said bore, the rear end of said key plug having a transversely extending slot open at a side of said key plug, said cylinder portion having a slot in the wall of the bore thereof with which the open end of said transverse slot may be made to register upon appropriate rotation of the key plug, a connecting bar having an end portion shaped to pass through said third-mentioned slot and into said transverse slot upon said two slots being brought into registry, thereby non-rotatably to interconnect said connecting bar and said key plug, and a member insertable into said third-mentioned slot for preventing movement of said connecting bar out of said transverse slot.

21. In lock construction, in combination, a casing having an open-ended cylinder portion containing a bore, a key plug having a key slot and rotatably fitted into said bore, the rear end of said key plug having a plurality of slots therein extending at an angle to each other and each opening in the periphery of said plug, the wall of said bore having an axial extent sufficient to encompass the portions of the plug in which said slots open, the wall of said bore having a portion cut away thereby to expose, upon appropriate rotation of said plug, the open end of a slot, a connecting bar having an end portion shaped to pass through said cut away portion of said bore wall and to enter a slot exposed to said cut away portion, thereby to become non-rotatably connected with said key plug, and releasable means carried by said casing for holding said connecting bar against movement out of the slot in which it has been entered.

22. In lock construction, in combination, a casing having an open-ended cylinder portion containing a bore, a key plug having a key slot and rotatably fitted into said bore, the rear end of said key plug having a plurality of slots therein extending at an angle to each other and each opening in the periphery of said plug, the wall of said bore having an axial extent sufficient to encompass the portions of the plug in which said slots open, the wall of said bore having a portion cut away thereby to expose, upon appropriate rotation of said plug, the open end of a slot, a connecting bar having an end portion shaped to pass through said cut away portion of said bore wall and to enter a slot exposed to said cut away portion, thereby to become non-rotatably connected with said key plug, said end portion of the connecting bar having a greater transverse dimension than the remainder of the connecting bar, said cylinder portion of the casing having a slot extending transversely of and to the rear of the rear end of said key plug, and a member having an aperture therein through which said remainder of the connecting bar extends but through which said end portion thereof cannot pass seated in said transverse slot and movable into or out of the latter in the same direction in which said connecting bar is movable into or out of a plug slot when the latter is exposed through said cut away portion of the wall of said bore.

23. In lock construction, in combination, a casing having an open-ended cylinder portion containing a bore, a key plug having a key slot and rotatably fitted into said bore, the rear end of said key plug having a plurality of slots therein extending at angle to each other and each opening in the periphery of said plug, the wall of said bore

having an axial extent sufficient to encompass the portions of the plug in which said slots open, the wall of said bore having a portion cut away thereby to expose, upon appropriate rotation of said plug, the open end of a slot, a connecting bar having an end portion shaped to pass through said cut away portion of said bore wall and to enter a slot exposed to said cut away portion, thereby to become non-rotatably connected with said key plug, said end portion of the connecting bar having a greater transverse dimension than the remainder of the connecting bar, and means coacting with said end portion for preventing movement in an axial direction of the connecting bar out of the slot in which it has been entered.

24. In lock construction, in combination, a casing having an open-ended cylinder portion containing a bore, a key plug having a key slot and rotatably fitted into said bore, tumbler means controllable by a key inserted into said key slot for coaction with said key plug and casing, an operating bar, means forming a detachable interconnection between said operating bar and the rear end of said key plug and capable of disconnection upon moving said connecting bar in the direction of a radius of said key plug, said detachable interconnection means including means for preventing movement of said connecting bar away from said key plug in the direction of the axis of the latter and said key plug having a groove extending in the direction of its periphery and said plug normally having such a position that a wall of said bore resists movement of said connecting bar along a radius of said key plug, and means projecting from said casing into said groove to prevent axial displacement of said key plug.

25. In lock construction, in combination, a casing having a bore for rotatably receiving therein a key plug and having a front end wall that is circular, there being a casing portion extending rearwardly of said front end wall for receiving tumbler means, said front end wall having a slot therein extending from the periphery thereof to and into communication with said bore and being of sufficient lateral expanse to extend in front of said tumbler portion of said casing, a key plug rotatably received in said bore and having a peripheral groove adjacent its forward end and substantially aligned with said slot, and a plate-like member of relatively hard metal fitted into said slot and thereby extending across and in front of said tumbler portion of the casing and extending into the peripheral groove of said key plug, thereby to hold the latter against axial displacement, and means inaccessible when said lock construction is installed for preventing withdrawing movement of said plate-like member relative to its slot.

26. A lock construction as claimed in claim 25 in which the means for preventing withdrawing movement of the plate-like member comprises a screw threaded through a wall of said slot other than the front wall therefor for blocking withdrawing movement of said plate-like member relative to its slot.

27. A lock construction as claimed in claim 25 in which the means for preventing withdrawing movement of the plate-like member comprises a flanged ring-like member receivable over said circular front end wall and closing the outer end of said slot, a flange of said ring-like member engaging to the rear of said front end wall.

28. In lock construction, in combination, a

- 5 casing having a cylinder portion containing a bore, a key plug rotatably fitted into said bore, the rear end of said key plug having a transversely extending slot open at a side of said key plug, said cylinder portion having a slot in the wall of the bore thereof with which the open end of said transverse slot may be made to register upon appropriate rotation of the key plug, a connecting bar having an end portion shaped to pass 10 through said registered slots and to enter into the transverse slot in the key plug, thereby to become non-rotatably connected with said key plug, said end portion of the connecting bar having a greater transverse dimension than the remainder of the connecting bar, and means carried by 15 said casing and projectable radially into said bore and to the rear of said greater-dimensioned end portion of the connecting bar, thereby to prevent disengagement of said connecting bar in an axial direction from said key plug.

20 29. In lock construction, in combination, a casing having a cylinder portion containing a bore, a key plug rotatably fitted into said bore, the rear end of said key plug having a transversely extending slot open at a side of said key plug, said cylinder portion having a slot in the wall of the bore thereof with which the open end of said transverse slot may be made to register upon appropriate rotation of the key plug, a connecting bar 25 having an end portion shaped to pass through said registered slots and to enter into the transverse slot in the key plug, thereby to become non-rotatably connected with said key plug, said end portion of the connecting bar having a greater transverse dimension than the remainder of the connecting bar, said casing having a recess adjacent its rear end communicating with said bore, and a member encircling said connecting bar adjacent said end portion thereof and received 30 into said recess as and when said connecting bar is inserted into said transverse plug slot upon registry of said two slots, for preventing disconnection of said connecting bar from said key plug in an axial direction.

bore, the rear end of said key plug having a transversely extending slot therein opening in the periphery of said plug, the wall of said bore having an axial extent sufficient to encompass the portions of said plug in which said slot opens at the periphery and the wall of said bore having a portion cut away thereby to expose, upon appropriate rotation of said plug, the open end of said slot, said slot being undercut, a connecting bar having an end portion shaped to pass through said cut away portion of said bore wall and to enter said slot when the latter is exposed to said cut away portion and to interfit with said undercut slot, thereby to become non-rotatably connected with said key plug and said connecting bar and key plug being thereby incapable of disconnection, except through movement in radial direction of said connecting bar through said cut away portion, and means for closing over said cut away portion of the wall of said bore, thereby to prevent exposure of said slot and to prevent movement in radial direction of said connecting bar.

32. In lock construction, in combination, a casing having an open ended cylinder portion containing a bore, a key plug rotatably fitted into said bore, the rear end of said key plug having a transversely extending slot therein opening in the periphery of said plug, the wall of said bore having an axial extent sufficient to encompass the portions of said plug in which said slot opens at the periphery and the wall of said bore having a portion cut away thereby to expose, upon appropriate rotation of said plug, the open end of said slot, said slot being undercut, a connecting bar having an end portion shaped to pass through said cut away portion of said bore wall and to enter said slot when the latter is exposed to said cut away portion and to interfit with said undercut slot, thereby to become non-rotatably connected with said key plug and said connecting bar and key plug being thereby incapable of disconnection, except through movement in radial direction of said connecting bar through said cut away portion, and spring-mounted means yieldably movable into or out of the cut away portion of the wall of said bore.

33. In lock construction, in combination, a casing having an open ended cylinder portion containing a bore, a key plug rotatably fitted into said bore, the rear end of said key plug having a transversely extending slot therein opening in the periphery of said plug, the wall of said bore having an axial extent sufficient to encompass the portions of said plug in which said slot opens at the periphery and the wall of said bore having a portion cut away thereby to expose, upon appropriate rotation of said plug, the open end of said slot, and a connecting bar having a T-shaped end portion which is movable through said cut away portion and into said plug slot, thereby to become non-rotatably connected with said key plug, said connecting bar having a retaining member relative to which said bar is rotatable but through which said T-shaped end portion cannot pass, said cylinder portion of said casing having a recess extending transversely to the axis of, and intersecting, said bore, and into which said retaining member is moved and received as and when said connecting bar is moved in a radial direction relative to the plug slot when the latter is exposed through said cut away portion.
